[57] CLAIM

The ornamental design for a handle for kitchen utensil, as shown and described.

DESCRIPTION

FIG. 1 is a perspective view of the handle for kitchen utensil showing my new design;

FIG. 2 is a front elevation of the utensil shown in FIG. 1; FIG. 3 is a side elevation thereof, the other side being identical;

FIG. 4 is a rear elevation thereof;

FIG. 5 is an elevation taken from one end of the utensil; and, FIG. 6 is an elevation view taken from the other end thereof. The broken line showing of a spatula in FIGS. 1-6 is for illustrative purposes only and forms no part of the claimed design.
